CLAIM

The ornamental design for an automotive tire, as shown and described.

DESCRIPTION

1. Automotive tire
- 1.1 is a left side elevation view of an automotive tire showing our new design;
- 1.2 is a right side elevation view thereof;
- 1.3 is a perspective view thereof;
- 1.4 is a front elevation view thereof;
- 1.5 is a top plan view thereof;
- 1.6 is an enlarged partial front elevation view thereof, wherein the enlargement area is indicated by the broken line bracket marked **1.6** in **1.4**.
